(57) **CLAIM**

I claim the ornamental design for a obstetric suction cup extractor, as shown and described.

DESCRIPTION

FIG. 1 is a perspective view shown from above of an obstetric suction cup extractor showing my new design; FIG. 2 is a perspective view thereof, shown from below; FIG. 3 is a perspective view thereof of the cup portion shown from above, with the handle removed for ease of illustration; FIG. 4 is a perspective view thereof, shown from below; FIG. 5 is a perspective view of the handle shown from above with the cup portion removed for ease of illustration; and, FIG. 6 is a perspective view thereof, shown from below.
